US0D1055121S

(12) **United States Design Patent** (10) **Patent No.:** **US D1,055,121 S**
(45) **Date of Patent:** **** Dec. 24, 2024**

(54) **CUTTER**

(71) Applicant: **Vermeer Manufacturing Company**,
Pella, IA (US)

(72) Inventors: **Claudio Carrafiello Verzilli**, Pella, IA
(US); **Joshua Dean Nossaman**, Pella,
IA (US)

(73) Assignee: **Vermeer Manufacturing Company**,
Pella, IA (US)

(**) Term: **15 Years**

(21) Appl. No.: **29/824,318**

(22) Filed: **Jan. 24, 2022**

(51) LOC (14) Cl. **15-09**
(52) U.S. Cl.
USPC **D15/139**

(57) **CLAIM**

The ornamental design for a cutter as shown and described.

DESCRIPTION

FIG. 1 is a front, top, right perspective view of a cutter.

FIG. 2 is a front, bottom, left perspective view of the cutter of FIG. 1.

FIG. 3 is a left side elevation view of the cutter of FIG. 1.

FIG. 4 is a right side elevation view of the cutter of FIG. 1.

FIG. 5 is a front elevation view of the cutter of FIG. 1.

FIG. 6 is a rear elevation view of the cutter of FIG. 1.

FIG. 7 is a top plan view of the cutter of FIG. 1; and,

FIG. 8 is a bottom view of the cutter of FIG. 1.

The portions of the cutter shown in broken lines form no part of the claimed design.

1 Claim, 8 Drawing Sheets
